UNITED STATES PATENT OFFICE.

CARL WINKLER, OF BERNE, SWITZERLAND.

MACHINE FOR CASTING STEREOTYPE-PLATES.

1,195,123.

Specification of Letters Patent. Patented Aug. 15, 1916.

Application filed April 5, 1915. Serial No. 19,405.

To all whom it may concern:

Be it known that I, CARL WINKLER, a citizen of the Swiss Republic, residing at Berne, in the Swiss Republic, have invented 5 new and useful Improvements in Machines for Casting Stereotype-Plates, of which the following is a specification.

This invention relates to machines for casting stereotype plates, and it has for its 10 object to cast such plates quickly and without any superfluous appendix of cast metal, so that the work and apparatus hitherto requisite for removing said appendix are avoided.

15 The invention also has for its object to save molten metal and consequently to effect an economy of fuel (to the extent of about 50 per cent.) and further, to enable plates to be cast at an essentially lower temperature 20 than has hitherto been possible.

The principal feature of the invention is that in casting the plates the mold is brought into immediate connection with the crucible.

25 Another feature of the invention is that molds for both curved and flat plates can be brought into immediate connection with the same crucible.

The invention finally relates to an improvement in crucibles for machines of this 30 kind, such improvement being characterized by a novel construction of the cock by which the connection between the crucible and mold is effected.

35 The accompanying drawings illustrate the invention by way of example.

Figure 1 is a sectional elevation of a machine embodying the invention and shows the connection between the mold and the 40 crucible. Fig. 2 is a similar view, this connection being interrupted, Fig. 3, a front elevation of the machine, partly in section; Fig. 4, a sectional elevation of a machine having a mold for curved plates and a second mold for flat plates, both combined with one crucible. Figs. 5, 6 and 7 show cross-sections of a form of construction of the cock by which the connection between the crucible and mold may be effected; Fig. 8 45 represents an appertaining longitudinal section.

In the arrangement shown in Figs. 1 to 3 a single mold is combined with the crucible. The furnace consists essentially of a shell 1, 50 crucible 2 disposed therein and having an elongated outlet 3 for the molten metal, and

of a base 5, which carries the shell 1, and, by means of supports 4, also the crucible 2; the base 5 carries the fire grate 6. To the base 5 another base 8 is fixed on which the 60 mold and its adjuncts rest. The base 8 has two guides 9 for rollers 10, the mold being movable on these rollers toward and away from the furnace. The mold consists of the shell 11 and two cores 12. Each of the cores 65 12 is mounted in a support 13 by means of an arm 14 so as to be rotatable on a horizontal axis. The shell 11 and cores 12 have hollows 15 which serve for heating or cooling the mold. A shaft 16, provided with a 70 hand lever 17, is connected at 20 with the base 5 by means of links 18 and a rod 19. This mechanism serves to move the mold toward the crucible, *i. e.* into the position for casting plates, or to move it away from the 75 crucible, when a projection 11' of the mold will cover and close the outlet 3, as will be seen from Figs. 1 and 2. On the shaft 16 and a second shaft 21 hooks 22 are arranged which serve to retain the cores 12 in the 80 position shown in Fig. 1, that is, to keep them in the shell 11 by engaging rollers 26 with which the cores are fitted, as indicated in Fig. 1. These hooks are actuated by the following device: To the shell 1 a guide 23 85 for a roller 24 is fixed, this roller being attached to the adjacent hook 22. The hooks are connected with each other by toothed segments 22' and are keyed on the shaft 21, but are loose on the shaft 16 so that they 90 can rotate on the latter.

This machine is used in the following manner: The shell 11 and the cores 12 are heated to about 140° by vapor entering the hollow spaces 15 through pipes *a*, the object 95 being to avoid the waste castings hitherto usual. The machine is then in the condition represented in Fig. 2, the projection 11' of the mold covering the outlet 3 of the crucible and the cores 12 being elevated. 100 The matrix is placed in a matrix holder of any well-known construction, and, with this device, is laid in the shell 11. It would also be admissible to arrange the matrix retaining device on the cores 12 and to place the 105 cores together with matrix and matrix holder into the shell 11. Thereafter the lever 17 is brought into the position shown in Fig. 1, with the result that the mold is moved on the rollers 10 toward the crucible 110 2, so that the inlet opening 3' of the mold will arrive under the outlet 3 of the pot,

while the hooks 22 engage the rollers 26 so as to retain the core 12 in the shell 11. When the opening 3' coincides with the opening 3 the molten metal in the crucible 2 enters the space 27 between the shell 11 and core 12. After this space has been filled the hot vapor formerly admitted into the hollow spaces 15 of the shell 11 and core 12 is cut off and replaced by warm water which cools the mold, whereupon said mold is returned by means of the lever 17 into the position shown in Fig. 2. During the movement of the mold the hooks 22 are brought out of engagement with the rollers 16, so that the core 12 is released and will move upward with the cast plate attached to it, which latter can now be removed from the core. The matrix held by the matrix holder is separated from the cast plate on 20 the latter moving upward and is returned into the shell, so that a number of castings can be immediately made from the same matrix. After the core has been moved upward with the cast plate, the second core 25 can be immediately placed in the shell, whereupon the mold can be again moved into the position shown in Fig. 1. The described arrangement thus allows one core to be alternately moved out with the cast 30 plate and the other core to be moved in for casting another plate.

The opening 3 of the crucible should preferably be as broad as the plate to be cast, so that the molten metal will enter the mold very rapidly. While casting the entire mass 35 of molten metal contained in the crucible acts as a head to insure that as much metal will enter the mold as may be necessary to properly fill it, the pressure thus produced being considerably higher than with the usual devices.

The device shown in Fig. 4 is essentially the same as the one just described, but has a mold for flat plates besides the mold for 45 curved plates with which the arrangement according to Figs. 1 and 2 is provided. The advantage due to this form of construction is that with one crucible both curved and flat plates can be simultaneously produced at a rate of working never attained before. The mold for flat plates consists of a part 11' and a second part 12' movable with regard to the part 11'. Both the flat mold and the curved mold 11, 12, which is 50 on the other side of the crucible 2 and is already known from the arrangement disclosed in Figs. 1 and 2, are movable relatively to the pot.

The outlet openings 3 of the pot 2 may be 60 regulated by a cock 28. A cock particularly adapted for the purpose of this invention is represented in Figs. 5 to 8. In the casing 29 of the cock there are chambers 30 which are in immediate connection with the crucible. The cock plug 31 has a recess 32 in

its circumference. When the plug 31 is in the position shown in Fig. 5 the molten metal flows through the chambers 30 into the recess 32 of the plug and thence into the mold. After the mold has been filled 70 the plug 31 is turned into the position represented in Fig. 6, the recess 32 retaining a quantity of metal which replaces and serves every useful purpose of the appendix hitherto obtained in casting plates. The 75 depth of the recess 32 is about equal to the thickness of the cast plate, in order that the latter may solidify in a perfectly reliable manner together with the metal in the recess 32. At an appropriate moment of the 80 solidifying process the plug 31 is turned into the position shown in Fig. 7, one edge of the recess 32 separating the molten metal contained in the recess 32 from the cast plate; the metal thus cut off is brought back 85 into the crucible owing to the rotation of the plug, the recess 32 preferably extending over the whole length or width of the cast plate.

It is to be understood that the invention 90 is not restricted in scope to the forms of construction illustrated and described, but that modifications may be made within the scope indicated by the appended claims, without departing from the spirit or sacrificing any of the advantages of this invention. For instance, instead of two cores, as 95 shown, only one may be used in any suitable arrangement adapted for the purpose.

What I claim and desire to secure by Letters Patent of the United States is:—

1. A machine for casting stereotype plates, comprising in combination, a fixed crucible having a slot shaped outlet, a mold 105 comprising a shell and a core movable into and out of the shell, the mold having an inlet opening, a horizontal support on which the mold is mounted to slide, means for moving the mold to and from the crucible, the said outlet and inlet being caused to coincide, when the mold is moved toward the crucible, means for controlling the outlet of the crucible, and means for retaining and releasing the core and controlled by the movement of the mold.

2. A machine for casting stereotype plates comprising in combination a crucible having a slot shaped outlet, a mold having an inlet opening, means for moving the mold to and from the crucible, the said outlet and inlet being caused to coincide when the mold is moved toward the crucible, and a horizontal plate projecting from one side of the mold and below the outlet of the crucible, said plate adapted to close the outlet upon 120 movement of the mold away from the crucible, as and for the purpose specified.

3. A machine for casting stereotype plates, comprising in combination a fixed crucible having a slot-shaped outlet, a mold 125

including a shell and a core movable into and out of the shell, the said mold having an inlet opening adapted to coincide with said outlet, a support provided with rollers on which the mold is mounted to slide, means for moving the mold toward or from the crucible, the said outlet and inlet being caused to coincide with each other when the mold is moved toward the crucible, and means for retaining and releasing the core controlled by the movement of the mold toward and from the crucible.

4. In a machine for casting stereotype plates, a crucible having a slot-shaped outlet, a mold including a shell and a core movable into and out of the shell, the mold having an inlet opening, rollers on which the mold is supported, a lever mechanism for moving the mold on said rollers toward and from the crucible, the said outlet and inlet being caused to coincide when the mold is moved toward the crucible, means for closing the said outlet when the mold is moved away from the crucible, and means controlled by the movement of the mold toward and from the crucible for retaining and releasing the core.

5. In a machine for casting stereotype plates, a shell, a crucible disposed therein and having an elongated outlet for the molten metal, a base carrying said shell and supporting said crucible, a mold including a shell and a core movable into and out of the shell, the mold having an inlet opening, a base fixed to the first mentioned base and on which the said mold rests, means for moving the mold on said base toward and from the crucible, the said outlet and inlet being caused to coincide when the mold is moved toward the crucible, means for engaging the core when the mold is moved toward the crucible to keep the same in the shell, the said means being controlled by the movement of the mold, and means for controlling the communication between the crucible and the mold.

In testimony whereof I have signed my name to this specification in the presence of two subscribing witnesses.

CARL WINKLER.
